(57) **CLAIM**

The ornamental design for a baitcast fishing reel, as shown.

DESCRIPTION

FIG. 1 is a perspective view from the top right side of a baitcast fishing reel showing our new design;

FIG. 2 is a rear elevation view thereof;

FIG. 3 is a front elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken line showing of environment in the drawings is for illustrative purposes only and forms no part of the claimed design.
